OF ONE-FOURTH TO HARRY C. SCHROEDER, OF OAKLAND, CALIFORNIA

REPEATING RUBBER BAND RIFLE

Application filed August 27, 1932. Serial No. 630,668.

This invention is a repeating rubber band rifle, and is specially directed to a rifle which may be loaded with a plurality of rubber bands, the rifle being adapted to shoot the bands in rapid succession, or one at a time as may be desired.

The main object of the invention is to provide a rifle which will shoot rubber bands and which may be loaded with a plurality of bands which may be shot successively from the rifle.

Another object of the invention is to provide a rifle as outlined with means for controlling the shooting of the bands, the control means providing for extremely rapid successive fire of the bands or for shooting the bands successively one at a time.

A further object of the invention is to provide sights for the rifle which sights will be automatically adjusted for the shooting of the various bands, whereby the sights will always be correct irrespective of the angular relation of the band being shot or projected.

Other objects and advantages of the invention will become apparent as the following description is read on the drawing forming a part of this specification, and in which similar reference characters are used to designate similar parts throughout the several views, of which:

Fig. 1 is a side elevation of my invention, loaded with a plurality of rubber bands.

Fig. 2 is a side elevation of the invention partly shown in section to show the operating or release mechanism for the rubber bands.

Fig. 3 is an enlarged fragmentary view of the band holding and band releasing means.

Fig. 4 is a section taken on line 4-4 of Fig. 3.

Fig. 5 is a section taken on line 5-5 of Fig. 3.

Fig. 6 is a view similar to Fig. 3, showing the releasing mechanism in position for releasing one of the bands.

The invention consists of a barrel 10, the

muzzle of which is provided with a concavity 11 adapted to retain the rubber bands 12 in position, the barrel terminating at its rearward end in a breech 13, which is provided on its upper surface with a plurality of projections or lugs 14, which may be formed in the material, or may be formed by means of pins, over which the rearward ends of the rubber bands 12 are to be secured as is clearly indicated in Fig. 1, the stock 15 being integral with the breech and being formed in the conventional manner.

The breech 13 is provided with a slot 16 in which the release 17 is slidably mounted for reciprocal movement throughout the length of the teeth 14, and the exterior of the two walls of the breech are each provided with a groove 18, these grooves extending throughout the length of the breech.

The release mechanism consists of a plate-like member 17 having a circular recess 19 formed in the upper end, in which is rotatably mounted a disc 20, the disc 20 being inserted sidewise into the recess and retained by the upwardly extending edges 21, which project beyond the horizontal center of the disc. Secured to the lower end of the release plate 17 are oppositely disposed guides 22, which are each provided with a tongue 23 which is slidable in the groove 18, the combination of the members 17 and 22 forming together, the trigger 24.

Sights are provided as indicated in Figs. 2, 4 and 5, the front sight consisting of a groove 25 which is formed in the top surface of the muzzle. The rear sight consists of an annular groove 26 formed in the disc 20, this groove extending entirely about the periphery of the disc whereby the sight is provided irrespective of the rotative position of the disc.

It will be noted that by means of the plurality of teeth or lugs 14, that a plurality of bands 12 may have one end placed over the muzzle, and retained in the concavity 11, the

other end of the bands being caught respectively over the successive teeth 14, the releasing mechanism 17 being in the forward position as shown in Fig. 1. By drawing back 5 on the trigger 24, the disc 20 is brought under the successive bands 12, raising them out of the recess and releasing them after they have passed the top edge of the teeth, the rotatable disc permitting the bands to be raised 10 sufficiently high to clear the teeth, and offering no restraint to the band when released. The trigger 24 may be drawn back sufficient to release only one band at a time if desired, or if drawn back quickly its full distance of 15 travel, the entire number of bands will be quickly and successively released, but in no case is it possible to obtain simultaneous release of two bands as is readily apparent.

The sights automatically take care of the 20 location of the band on the teeth 14 as it will be noted that a band passing over the muzzle and extending over the first tooth will be deflected downwardly when released more than another band which extends over the last 25 tooth, and that the deflection will be dependent on the top of the disc 20 relative to the muzzle 11 and as the sight is formed in the disc 20, the disc deflection is compensated for by the positioning of the sight always at the 30 point of releasing of the band.

Having described an operative device it will be understood that variations in construction and arrangement of parts which are consistent with the appended claims may be 35 resorted to without detracting from the spirit or scope of the invention or sacrificing any of the advantages thereof.

We claim:

1. Releasing means for a rubber band rifle 40 comprising a sliding member and a disk rotatable therein, said disk peripherally cooperating successively with tensioned rubber bands to release the bands.

2. Releasing means for rubber bands and a 45 rear sight for a rubber band rifle comprising a sliding member and a disk rotatable therein, said disk peripherally cooperating successively with the tensioned rubber bands to release the bands, said disk having a peripherally formed annular groove to form the rear sight for the rifle.

3. In combination with a rubber band rifle, 55 releasing means for the tensioned rubber bands comprising a trigger slidable in the breech of the rifle and having a circular recess formed in the upper portion of the trigger and a disk rotatable in the recess and extending above the top of the trigger, said disk cooperating successively with the tensioned 60 rubber bands as the trigger is slid back, for releasing the bands.

4. In combination with a rubber band rifle, 65 releasing means for the tensioned rubber bands comprising a trigger slidable in the breech of the rifle and having a circular re-

cess formed in the upper portion of the trigger and a disk rotatable in the recess and extending above the top of the trigger, said disk cooperating successively with the tensioned rubber bands as the trigger is slid back, for releasing the bands, and a rear sight consisting of an annular groove formed in the periphery of the disk and coincidentally adjustable for the band to be released.

5. Releasing means for a rubber band rifle 70 comprising, in combination with stepped tensioning means for a plurality of rubber bands; an elongated slot formed vertically through the breech and longitudinally thereof, a member mounted for reciprocal movement in the slot and a disk rotatable in a circular recess formed in the upper portion of the member, said disk forming a non-resistant cam for releasing the tensioned bands 75 successively.

6. Releasing means for a rubber band rifle comprising, in combination with stepped tensioning means for a plurality of rubber bands; an elongated slot formed vertically through the breech and longitudinally thereof, a member mounted for reciprocal movement in the slot and a disk rotatable in a circular recess formed in the upper portion of the member, said disk forming a non-resistant cam for releasing the tensioned bands 80 successively, and an annular groove peripherally formed in the disk to form an automatically adjusted rear sight for the rifle.

7. Releasing means for tensioned rubber 85 bands comprising a sliding member, a disk rotatably mounted in the sliding member, the disk forming a cam to release the rubber bands.

8. Releasing means for tensioned rubber bands comprising a sliding member, a disk 90 rotatably mounted in the sliding member, the disk forming a cam to release the rubber bands, and an annular groove peripherally formed in the disk and forming a rear sight.

9. Tensioning and releasing means for a rubber band rifle comprising a breech provided on the upper surface with a series of back-cast teeth, and a cam member slidably in the breech and extending above the top of the teeth, said cam member consisting of a disk rotatable in a circular recess formed in a sliding member.

10. Tensioning and releasing means for a rubber band rifle comprising a breech provided on the upper surface with a series of back-cast teeth, and a cam member slidably in the breech and extending above the top of the teeth, said cam member consisting of a disk rotatable in a circular recess formed in a sliding member, said disk forming a rear sight for the rifle by means of a peripheral annular groove formed in the disk.

11. A rubber band rifle comprising a barrel having a concavity formed in the muzzle and a front sight consisting of a groove 130

formed in the top adjacent the nozzle, a breech having longitudinally formed therethrough in a vertical plane, an elongated slot, and a series of back-cast teeth formed in the upper surface of the breech, a releasing member slideable in the slot and having a rotatable rubber-band-releasing cam extending above the top of the teeth, a peripheral groove formed in the cam providing a rear sight and a stock integral with the breech.

In testimony whereof we affix our signatures.
